UNITED STATES PATENT OFFICE.

HARRY CHRISTENSEN AND EDMOND L. BRUNSWICK, OF CHICAGO, ILLINOIS.

DESIGN FOR A LIGHT FIXTURE.

Application filed December 31, 1921. Serial No. 526,403. Term of patent 3½ years.

To all whom it may concern:

Be it known that we, HARRY CHRISTENSEN and EDMOND L. BRUNSWICK, citizens of the United States, residing at Chicago, in the county of Cook and State of Illinois, have invented a new, original, and ornamental Design for a Light Fixture; of which the following is a specification, reference being had to the accompanying drawing, forming part thereof.

The figure is an elevational view of a light fixture showing our new design.

The portion indicated in full line outline in the drawing is ornamented in the same manner as the portion more fully illustrated.

As illustrated, use as a ceiling fixture is intended, the lower portion being adapted to carry a shade holder, as indicated in dotted lines.

We claim:

The ornamental design for a light fixture as shown.

In witness whereof, we hereunto subscribe our names, this 28th day of December, 1921.

EDMOND L. BRUNSWICK.
HARRY CHRISTENSEN.
